United States Patent Office

Des. 212,598
Patented Nov. 5, 1968

212,598

PORTABLE STAND FOR ELECTRONIC EQUIPMENT OR SIMILAR ARTICLE

Allen R. Stakee, 16149 Janine Drive,
Whittier, Calif. 90603

Filed Dec. 18, 1967, Ser. No. 9,832

Term of patent 14 years

(Cl. D14—3)

FIGURE 1 is a perspective view of a portable stand for electronic equipment or similar article;

FIGURE 2 is a side elevational view thereof;

FIGURE 3 is a top plan view of such stand; and

FIGURE 4 is a rear elevational view thereof.

I claim:

The ornamental design for a portable stand for electronic equipment or similar article, substantially as shown.
